SANITATION SYSTEM

BACKGROUND OF THE INVENTION

1. Field of the Invention

This invention is in the field of sanitation apparatus, wherein waste products are treated by filtration and by chemical action, with recirculation of the filtrate and the sludge or solids are accumulated in a disposable bag which can be disposed of without difficulty.

2. Description of the Prior Art

The apparatus of the present invention is primarily intended for maritime use but could also be used for storage in trailers or camp sites, or the like.

It has heretofore been the practice on smaller boats particularly, to discharge waste products directly into the water course. With the increasing emphasis on pollution control, however, this type of disposal system is unsatisfactory.

The present invention provides a sanitation assembly which is completely self-contained and does not require any connection outside of the hull of the boat for flushing water intake or for exhausting. The unit is completely portable so that it can be stored on a bulkhead, in a closet, or otherwise supported without difficulty.

SUMMARY OF THE INVENTION

The apparatus of the present invention may be used in connection with a marine head or the like. The discharge from the head is introduced by means of a suitable conduit into a disposable inner bag of the assembly, preferably consisting of a pair of panels of heat sealable vinyl resin, heat sealed along their marginal edges. Confined between the two panels is a foraminous filter member which is locked in place by heat sealing its edges to the marginal edges of the two panels. An inlet in the top of the bag introduces the discharge from the head into a disposable bag, and a discharge tube is provided on the opposite panel in spaced relation to the inlet so that the liquid must flow through the screen in passing from the inlet to the discharge. In accordance with an improved form of the present invention, the medial portion of the two panels is also heat sealed together, thereby providing a restricted flow path for the materials, and eliminating a direct path from the inlet to the discharge. The constriction thus provided channels the flow down one side of the bag, across the bottom, and up the other side to the discharge end.

Initially, a small amount of water is introduced into the bag, together with sufficient chemical treating agents to treat a predetermined number of cycles. After the predetermined number of cycles has occurred, the disposable bag can be removed, sealed, and delivered to the dock for disposal by a suitable means.

BRIEF DESCRIPTION OF THE DRAWINGS

FIG. 1 is a view of the complete installation of the present invention in operative relation;

FIG. 2 is a side elevational view of the sanitation assembly of the present invention;

FIG. 3 is a front elevational view of the assembly of FIG. 2, with portions thereof broken away to illustrate the interior construction more completely;

FIG. 4 is a front elevational view of the disposable bag itself;

FIG. 5 is a cross-sectional view taken substantially along the line V-V of FIG. 4;

FIG. 6 is a fragmentary view of a corner of the disposable bag after a clamp has been applied to seal the interior of the bag for disposal; and

FIG. 7 is a view taken along the line VII-VII of FIG. 6.

DESCRIPTION OF THE PREFERRED EMBODIMENTS

In FIG. 1, reference numeral 10 indicates generally a toilet assembly which is fastened to a deck 11 of the boat. The discharge of the assembly 10 passes by means of a conduit 12 through a suitable pump into an inlet tube 13 of the improved

sanitation assembly generally indicated at reference numeral 14 in the drawings. The discharge effluent from the assembly 14 is recirculated for flushing purposes by means of a discharge tube 15 which is connected to a conduit 16 by means of a hose clamp 17. A pump 18 serves to withdraw the discharge effluent and reintroduce it into the assembly 10 for flushing purposes on the next cycle of operation.

As best illustrated in FIGS. 2 and 3 of the drawings, the outer receptacle of the assembly may consist of an enclosure 19 composed of a flexible material such as a heavy gauge plastic. A plurality of straps 20 and 21 extend across the back of the enclosure 19 to permit the entire assembly to be mounted on hooks on the bulkhead or to accommodate a pair of rods which in turn can be detachably secured to the bulkhead or a closet or the like.

As best illustrated in FIG. 3, portions of the bottom of the enclosure 19 are folded over to provide flaps 22 and 23 which are secured to the remainder of the container by means of rows of stitching 24 and 25. This type of construction eliminates seams in which the material could collect.

The outer container 19 also has a top flap 26 which is secured to the body of the container 19 by means of suitable fastening means 27.

Turning now to the novel replaceable bag assembly which forms an important feature of the present invention, it will be seen from FIGS. 4 and 5 that the assembly consists of a pair of thermoplastic panels 31 and 32 which are heat sealed together along most of or all of their abutting marginal edges to provide a heat sealed seam 33 at one lateral edge of the bag, a heat sealed bottom seam 34 and a heat sealed seam 35 at the other lateral edge. The top edges are also sealed as indicated by a seal 36. Immediately below the top edge seam 36, there is provided a rectangular heat sealed area 37 in which a pair of slots 38 and 39 are formed to serve as handles for lifting the disposable bag and carrying it to a disposal site.

The panels 31 and 32 are cut away as indicated in FIG. 4 to form tabs 40 and 41 adjacent the upper corners of the disposable bag assembly. Heat sealed seams 42 and 43, respectively, separate the tabs 40 and 41 from the remainder of the bag. The front panel 32 is provided with a slot 44 for receiving the inlet tube 13 and the back panel 31 is provided with a slot 45 for accommodating the discharge tube 15. The tab 41 has been bent forward in the showing of FIG. 4 to illustrate the structure more clearly.

Confined between the panels 31 and 32 is a foraminous filter member such as a screen 46 preferably consisting of a heat sealable thermoplastic screening material such as nylon. The mesh size of the screen may be of the type employed for window screening, for example. The marginal edges of the screen 46 are confined in heat sealed relation within the seams 33, 34, 35 and 36, as best illustrated in FIG. 5 of the drawings.

A medial heat sealed strip 47 is also provided to channel the flow of the material through the bag. When the material is introduced by means of the tube 13 extending through the slot 44, the pressure of the heat sealed medial strip 47 provides a flow of liquid which is channeled down the left side, across the bottom and then up to the discharge site which consists of the tube 15 extending into the slot 45. Since the slot 44 and the slot 45 are on opposite sides of the screen 46, the liquid must pass through the screen 46 in flowing from the inlet end to the discharge end of the bag.

Initially, a relatively small amount of water is introduced into the interior of the bag, together with enough chemical treating agents to accomplish, for example, 40 cycles of operation. The chemical treating agents are commercially available materials and their exact composition does not form any part of the present invention. Generally, they are ferric hydroxides, lime, alum or the like.

With each cycle, the amount of liquid effluent discharged through the discharge tube 15 increases, and this effluent is recirculated back into the head for flushing purposes by the pump 18. After the predetermined number of cycles of operation, for example, forty, the solids retained by the screen have

built up sufficiently so that the bag can be disposed of in its entirety. Then, the inlet tube 13 and the discharge tube 15 are withdrawn from the slots 44 and 45, respectively, and the tabs 40 and 41 are folded over as illustrated in FIGS. 6 and 7, whereupon a clamp 51 is placed over the thus sealed ends. The clamp 51 includes a strip 52 and a strip 53 pivotally secured together by means of a pin 54. The strip 53 has a downwardly extending flange portion 55 which embraces the strip 52 tightly and serves to clamp the folded over portions of the tab 40 into sealed engagement. The sealed inner bag can then be taken to a dock and disposed of in any convenient manner.

From the foregoing, it will be understood that the present invention provides a readily disposable sanitation apparatus for maritime use or the like. The apparatus is completely portable and can be attached at any suitable location. The disposable bag can be made quite economically with conventional materials.

It will be evident that various modifications can be made to the described embodiments without departing from the scope of the present invention.

I claim:

1. A sanitation assembly comprising an outer enclosure, a flexible inner bag removably received within said enclosure, said inner bag having a front wall and a rear wall sealed together along their marginal edges, said inner bag having an inlet portion including a slot in said front wall for receiving an inlet conduit, an outlet portion including a slot in said rear wall for receiving a discharge conduit, a foraminous filter element sealed at said marginal edges to said front and rear walls and extending completely across the enclosure provided by said front and rear walls.
2. The assembly of claim 1 in which said slots are located in tabs disposed at the upper corners of said bag, said tabs being foldable relative to the remainder of said bag to permit clamping said tabs against the walls of said inner bag.
3. The assembly of claim 1 in which said front wall and said rear wall are sealed together in the medial portion of the inner bag to provide a confined flow path paralleling the edges of said bag for material introduced into said inlet portion and flowing to said outlet portion.
